COMBINED TONGUE DEPRESSOR AND MOUTH BLOCK

Frank Scaler, Jr., 243 Mangels Ave.,
San Francisco, Calif. 94131

Filed Feb. 28, 1968, Ser. No. 10,776

Term of patent 14 years

(Cl. D83—12)

FIG. 1.

FIG. 2.

FIG. 3.

FIG. 4.

FIG. 5.

FIG. 1 is a perspective view of a combined tongue depressor and mouth block, showing my new design;

FIG. 2 is a top plan view thereof;

FIG. 3 is a side elevation thereof;

FIG. 4 is an end elevation as seen from the left of FIG. 1; and

FIG. 5 is an end elevation as seen from the right of FIG. 1.

I claim:

The ornamental design for a combined tongue depressor and mouth block, as shown.
